(57) **CLAIM**

The ornamental design for an elastic break brake, as shown and described.

DESCRIPTION

FIG. 1 is a perspective view of the elastic break brake;
FIG. 2 is a front elevation view thereof;
FIG. 3 is a back elevation thereof;
FIG. 4 is right side elevation view thereof;
FIG. 5 is a left side elevation view thereof;
FIG. 6 is a top plan view thereof; and,
FIG. 7 is a bottom plan view thereof.
The broken lines in the drawings represent unclaimed subject matter and form no part of the claim.
